(57) **CLAIM**

The ornamental design for a mounting bracket for a radio frequency identification (RFID) tag reader, as shown and described.

DESCRIPTION

FIG. 1 is a perspective view of a mounting bracket for a radio frequency identification (RFID) tag reader showing our new design;

FIG. 2 is a perspective view thereof, shown in an alternate environment;

FIG. 3 is a rear elevation view thereof;

FIG. 4 is a front elevation view thereof;

FIG. 5 is a top plan view thereof;

FIG. 6 is a bottom plan view thereof;

FIG. 7 is a left side elevation view thereof; and,

FIG. 8 is a right side elevational view thereof.

The broken line environment in FIGS. 1 and 2 is for illustrative purposes only and forms no part of the claimed design.
